PATENTED JULY 30, 1907.

B. S. DEAN.

PNEUMATIC OPERATING DEVICE FOR MUSICAL INSTRUMENTS
AND MUSICAL INSTRUMENT PLAYERS.

APPLICATION FILED DEO. 12, 1906.

UNITED STATES PATENT OFFICE.

BENJAMIN S. DEAN, OF SAN FRANCISCO, CALIFORNIA.

PNEUMATIC OPERATING DEVICE FOR MUSICAL INSTRUMENTS AND MUSICAL INSTRUMENT PLAYERS.

No. 862,060.

Specification of Letters Patent.

Patented July 30, 1907.

Application filed December 12, 1905. Serial No. 291,382.

To all whom it may concern:

Be it known that I, BENJAMIN S. DEAN, a citizen of the United States of America, and a resident of San Francisco, county of San Francisco, State of California, have invented certain new and useful Improvements in Pneumatic Operating Devices for Musical Instruments and Musical-Instrument Players, of which the following is a specification, reference being had to the accompanying drawings, forming a part thereof.

10 This invention relates to improvements in pneumatic operating devices for musical instruments and musical instrument players, and consists in an improved pneumatic means whereby varying degrees of force may be applied for the purpose of operating the lever by which 15 individual tones are produced in musical instruments and musical instrument players, such lever being represented, for instance, by the keys of a piano or the playing levers of a piano player. The value of the tone produced depends upon the impactive force applied, and, 20 in the present invention, this force is varied by means of a plurality of pneumatic devices connected with a single element, each pneumatic device capable of imparting in itself a different degree of force, the said pneumatic means capable of being employed alone or 25 with another or others of the same group. By this means as many as seven different values may be represented by only three pneumatic devices, for, if the pneumatic devices have values of say one, two and four units, such units employed alone and in the various 30 combinations will represent every integral number of units from one to seven. These pneumatic devices may conveniently be secondary pneumatics controlled in their action from the primary pneumatic devices, as is common in the art of self-playing instruments and instrument players.

My improvements herein are particularly adapted for employment in connection with a system of control described in a co-pending application filed Nov. 25th, 1905 and serially numbered 288,987, in which the different pneumatic devices are selectively employed under the control of a perforated record sheet; said record sheet having a perforation for each of the pneumatic devices.

In order that my invention may be fully understood, 45 I will now describe an embodiment thereof with reference to the accompanying drawing and will then point out the novel features in claims.

In the drawings: Figure 1 is a view in side elevation of operating mechanism embodying my invention. 50 Fig. 2 is a transverse sectional view of the same along the line 2--2 of Fig. 1. Fig. 3 is a top view of three of the mechanisms side by side, with parts broken away.

Reference characters 7, 8 and 9 designate primary pneumatic devices contained in a stationary support 6

and in open communication with an exhaust chamber 55 10. These pneumatic devices are controlled in their operation by air admitted along conduits 11, 12 and 13, respectively. These primary pneumatic devices each include a valve 14 which normally closes a passage 15 through the diaphragm chamber of the primary 60 pneumatic with the exhaust chamber 10. Upon operation of a primary pneumatic device, as by venting atmospheric air into the same through its controlling channel, the valve 14 is lifted to open the passage 15 and at the same time to close a passage 16. The passage 16 leads to atmospheric air and is normally in open communication with a passage 17 leading to the secondary pneumatic device controlled by that particular primary pneumatic device. When the valve 14 closes the passage 16, thereby closing communication 70 between the passage 17 and atmospheric air, it at the same time opens communication between the passage 17, through the passage 15 and the diaphragm chamber of the primary pneumatic device, and the exhaust chamber 10. 75

18, 19 and 20 designate secondary pneumatic means, each constructed in the form of a collapsible bellows chamber. The lower wall of the bellows is made stationary, while the upper wall of each of the bellows of the central pneumatic devices of any one group is 80 secured to a lever 21. This lever 21 is fulcrumed at 22 to any suitable support, and is provided at its opposite end with a link 23, the opposite end of which connects with any suitable tone element actuator.

From the foregoing it will be understood that the 85 bellows 18, 19 and 20, constituting the said secondary pneumatic devices, are all normally open to atmosphere, and are hence all distended in their normal positions. Operation of any one of the primary pneumatic devices 7, 8 or 9 will close the secondary pneumatic device controlled thereby, to atmosphere and open same to exhaust. The result will be a collapsing 90 of the particular bellows and a drawing down of the lever 21. This, through its connection 23, will operate the tone actuator for the production of the individual tone selected. It will also be readily understood that if two of the primary pneumatic devices of any group are operated simultaneously, the corresponding secondary pneumatic devices of the same group will be simultaneously operated, whereby an 100 additional impactive force will be given to the lever 21, and a correspondingly additional force transmitted to the tone actuator, while, if all three of the devices are simultaneously operated, a still greater impactive force will be imparted to the lever and the tone actuator. 105

As above stated, the secondary pneumatic devices have preferably different values, and they may be arranged to have such different values in different ways

as may be desirable. I have shown this in a simple form in the drawings by arranging the said pneumatic means at different distances from the pivotal center of the lever 21, the pneumatic devices 18 and 19 being of about the same capacity but having different effective values by being placed one nearer, and the other further away from, the fulcrum or pivotal center 22. Thus, in the arrangement shown, the pneumatic device 19 has an effective force upon the tone actuator 10 representing a value of say two units to one unit of effective force of the pneumatic device 18. The pneumatic device 20 is arranged as of greater capacity than that of the other devices, and is also arranged still further away from the pivotal center 22. Thus the 15 pneumatic device 20 may be considered to have a value representing say four units of effective force. By this means seven different units of value may be available, for the employment of the pneumatic device 18 alone will give a value of one unit, the device 19 alone two units, the devices 18 and 19 together three units, the device 20 alone four units, the devices 18 and 20 five units, the devices 19 and 20 six units, and the devices 18, 19 and 20 all together seven units.

In Fig. 3 I have shown three groups of pneumatic 25 devices, each comprising three such devices connected with individual levers 21. Each group is intended to represent one tone to be produced, as will be well understood.

I am not claiming broadly herein the controlling of a 30 tone by means of governing devices comprising a plurality of pneumatic controlling elements therefor, as that is included in the co-pending application above referred to, but

What I claim herein is:

35 1. Mechanism of the class described comprising a musical instrument operating element consisting of a fulcrumed lever, a plurality of pneumatic devices of bellows form connected directly with said lever at different distances from its fulcrum, and independent primary pneu-

matic devices, one for each said bellows pneumatic device, 40 arranged in direct communication therewith and for direct control thereof.

2. The combination with an exhaust chamber and a lever pivotally connected to a wall thereof, said lever constituting a musical instrument operating element, of a plurality of independent pneumatic devices of bellows form, 45 one wall of each of said devices directly secured to the said lever but at a distance from the pivotal support thereof different from that of the others, and the other wall of each of said devices secured to a part stationary with the 50 said exhaust chamber, primary pneumatic devices one for each first said pneumatic device, said primary pneumatic devices comprising diaphragm controlled valves which open and close ports and passages to and from said individual bellows devices, and means for controlling the operation of said primary pneumatic devices. 55

3. In a device of the character described, the combination with a support, and a vacuum chamber to one wall of which the said support is secured, of a lever pivotally secured to the said wall of the vacuum chamber above the 60 upper surface of the support, a plurality of pneumatic devices of bellows form arranged between the said lever and support but at different distances from the pivotal support of said lever, said pneumatic devices being normally open to atmosphere, primary pneumatic devices, one for each 65 said first named pneumatic device, arranged in said support immediately adjacent to said first named pneumatic devices, said primary pneumatic devices comprising each a diaphragm and a valve connected thereto, said diaphragm arranged in normal open communication on both sides 70 thereof with said vacuum chamber, said support having passages controlled by said valves leading from the upper side of the diaphragm of each said primary pneumatic device to the bellows of each said secondary device, respectively, said passages being normally closed by the valves 75 of said primary pneumatic devices, and means for admitting air to the primary pneumatic devices upon the opposite side of the diaphragms thereof to lift the individual valves of same, and thereby to open the last said passages and at the same time to close communication between the 80 said bellows chamber and the atmosphere.

BENJAMIN S. DEAN.
